COMBINED BUMPER GUARD AND LAMP LENS HOUSING

Richard F. Baird, Oak Park, Mich., assignor to Chrysler Corporation, Highland Park, Mich., a corporation of Delaware

Application June 11, 1956, Serial No. 41,865

Term of patent 7 years

(Cl. D48—32)

Fig. 1 is a side elevational view of a combined bumper guard and lamp lens housing, showing my new design;

Fig. 2 is a front elevational view thereof;

Figs. 3 and 4 are sectional views taken on the lines 3—3 and 4—4, respectively, of Fig. 2; and

Fig. 5 is a sectional view on the line 5—5 of Fig. 1.

The characteristic features of my design reside in the portions shown by means of full lines in the drawing.

I claim:

The ornamental design for a combined bumper guard

and lamp lens housing, substantially as shown and described.
